UNITED STATES PATENT OFFICE.

GEORGE STRECKER, OF CHICAGO, ILLINOIS.

FOOT-PROPELLED VEHICLE.

SPECIFICATION forming part of Letters Patent No. 605,028, dated May 31, 1898.

Application filed August 14, 1897. Serial No. 648,290. (No model.)

To all whom it may concern:

Be it known that I, GEORGE STRECKER, of Chicago, in the county of Cook and State of Illinois, have invented certain new and useful Improvements in Foot-Propelled Vehicles; and I do hereby declare the following to be a full, clear, and exact description of the invention, such as will enable others skilled in the art to which it appertains to make and use the same.

This invention relates to improvements in foot-propelled vehicles, and has special reference to that class which is actuated by the rocking of the body.

15 A further object of the invention is to so construct and arrange the parts as to give a life-like motion to the animals constituting the rocking body.

The invention consists of the novel features of construction hereinafter described in the specification, particularly pointed out in the claims, and illustrated by the accompanying drawings, in which—

Figure 1 is a perspective view of my invention. Fig. 2 is a bottom plan view. Fig. 3 is a sectional side elevation, and Fig. 4 shows a modification.

Referring to the accompanying drawings, 1 indicates the body, which is formed like the ordinary "shoo-fly," the sides of which may be formed into the shape of any particular animal desired.

2 indicates the crank-pins, having the central crank portions 3, which extend oppositely, as illustrated.

35 4 are the wheels, which are secured to the crank-pins, while the body is loosely mounted upon said pins, the latter passing loosely through the legs of the animal.

5 40 5 is a reach or balance rod which is loosely mounted at one end upon the crank portion of the rear pin, and on its opposite end is formed with a slot 6, in which the crank portion of the front pin freely moves. This rod 45 or reach serves to retain the cranks in the same relation to each other as the crank-pins are revolved.

The wheels are weighted so that they are

balanced, and a child seated in the body by rocking back and forth causes the front and 50 rear ends of the body to rise and fall alternately and at the same time propel the vehicle, and the animals move in a very life-like manner. The child seated in the body may 55 propel the same by pressing with his feet upon a balance-rod, as will be understood.

In Fig. 4 I have shown a structure by which the front wheels are permitted to turn. In this construction a plate 13, resembling one of the plates of the fifth-wheel of a wagon, is 60 journaled upon the front pin, while above the said plate is a corresponding plate 14, upon which the figure rests. If so desired, a rod 15 can be rigidly secured to the plate 13 and passed through the upper plate, said rod 65 being provided with a cross-bar 16, by means of which the front pin can be turned by the rider.

I do not limit myself to the particular form of rocking body, as the same may be in the 70 representation of many different kinds of animals; nor do I limit myself to the use of the device for propelling the shoo-fly, as it may be manufactured as a toy to be moved across the floor by a child.

Having thus described my invention, what I claim, and desire to secure by Letters Patent, is—

1. In a device of the character described, the combination with a series of wheels and 80 crank-pins on the inner sides thereof, of a body loosely mounted upon said pins, and a connection between the crank portions of the pins having a sliding engagement with one of said crank portions, substantially as de- 85 scribed.

2. In a device of the character described, the combination with a series of wheels, of crank-pins having their crank portions disposed oppositely, a body loosely mounted 90 upon said pins, and a reach-rod connecting the crank portions of the pins, and having a limited sliding movement thereon, substantially as set forth.

3. In a device of the character described, 95 the combination with a series of wheels, of

crank-pins connecting said wheels in pairs, a body loosely mounted thereon, and a rod loosely connected at one end to the crank portion of one of said pins and slotted at its opposite end to receive the crank portion of the opposite pin, substantially as set forth.

In testimony whereof I have signed this

specification in the presence of two subscribing witnesses.

GEORGE STRECKER.

Witnesses:
